UNITED STATES PATENT OFFICE

JOHN C. MORGAN, OF LOS ANGELES, CALIFORNIA

HATBAND PROTECTIVE MEANS

Application filed November 28, 1927. Serial No. 236,158.

My invention relates to shields and more particularly to a shield for protecting the crown and hat band of a hat from being soiled by perspiration from the head and 5 forehead of the wearer.

The general object of my invention is to provide a simple and inexpensive shield for effectively diverting the perspiration from a wearer's forehead and satisfactorily dispersing the same and thereby prevent such perspiration from soaking through the crown and hat band of the wearer's hat.

Another object is to provide a shield of the character stated which may be easily and 15 quickly attached to and detached from a hat.

Another object is to provide a shield of the character stated that is also adapted for shading the eyes of the wearer of the hat to which my novel shield is attached.

20 A further object is to provide a device of the character stated which may be used as an advertising medium but which advertising data placed thereon will not contact with the skin of the wearer.

25 The invention includes the parts and combinations of parts more specifically herein-after referred to.

Other objects, advantages and features of invention may appear from the accompanying drawings, the subjoined detail description and the appended claims.

The accompanying drawings illustrates the invention in some of the forms I at present deem preferable.

30 Figure 1 is a perspective view of my novel device shown attached in place on a hat with which it is used in combination.

Fig. 2 is a fragmental sectional view of the shield taken on line 2—2 of Fig. 1, parts 35 are broken away to disclose interior construction.

Fig. 3 is a fragmental sectional view of the shield and hat taken on line 3—3 of Fig. 1.

Fig. 4 is a fragmentary elevation of the 40 shield as viewed from the inside of the hat and showing a modified form of attaching means.

Fig. 5 is a view analogous to Fig. 3 showing a modified form of my shield as adapted for 45 use as an eyeshade.

Fig. 6 is a sectional view analogous to Fig. 3 on an enlarged scale showing another modified form of my shield also adapted for use as an eyeshade.

Fig. 7 is a fragmentary enlarged sectional view of the lower end of the device shown in Figs. 1 and 3.

Fig. 8 is a longitudinal sectional view taken on a plane indicated by line 8—8, Fig. 7 showing a modified form of perspiration absorption or dispersing means. Parts are left in elevation to illustrate ventilating arrangements.

My shield comprises a sheet 1 of non-absorbent material such as thin flexible celluloid, rubber or the like, which may, if desired, be transparent for the purpose herein-after described. The sheet 1 is curved to conform to the contour of the forward portion of the inside of the crown of a hat 2 and 50 may be bent upon itself at its upper edge outwardly and downwardly to form a slightly outstanding depending flange 3, adapted to be slipped over the upper edge and outer side of the sweat band 4 of the hat 2 thereby providing securing means *a* for holding the sheet 1 against the inner side of the front portion of said sweat band in position to engage the forehead of the wearer of the hat. The flange 3 for engaging the sweat band may be a 55 single continuous flange or it may be a series of spaced flanges 3' as shown in Fig. 4. By reason of such arrangement perspiration from the wearer's forehead is prevented from coming into contact with said sweat band and soaking through the same and thence through the crown 5 and outside or hat band 6 of the hat and soiling said band 6 as has heretofore been the case. The sheet 1 is bent 60 forwardly and outwardly at its lower edges at an angle to form a slightly forwardly extending lower flange 7 which extends under and adjacent the brim 8 of the hat 2 for a short distance. The forward or lower edge of said flange 7 is turned under and formed into a tubular bead 9 which may be terminated a slight distance from the flange 7 or provided with any suitable openings 10 in its inner wall adjacent the under side of the lower flange 7, and through which openings

65 70 75 80 85 90 95 100

perspiration may run from the inner side of the sheet 1 and under side of the flange 7 into the tubular bead 9 where the perspiration is dispersed or evaporated by the air passing 5 through the bead through its open ends 11.

In Figs. 3, 5, and 6 I have provided the securing means *a* with prongs 12 that may be suitably secured to or struck out of the sheet 1 and forced through the sweat band 10 and into an opening 13 in the upper flange 3 (see Fig. 6), thus locking the shield on the sweat band so that it cannot be accidentally withdrawn from the sweat band.

Advertising matter 14 of any suitable character 15 may be placed on the outer side of the sheet 1 when a transparent sheet is used, so that it may be seen through said transparent sheet and by such arrangement it will not come into contact with the forehead of the 20 wearer of the hat and be rubbed off the sheet by the friction and perspiration of the wearer's head upon said sheet.

In the form of my invention shown in Fig. 5, I have provided a flange 15 that extends 25 forwardly and downwardly from the member 1 and bead 9 and provides an eye shade.

In the form of my invention shown in Fig. 6, the lower flange 7 and the bead 9 are eliminated and the sheet 1 is provided with 30 a flange or extension 16 that is bent forwardly and downwardly at an incline at its lower edge to form an eye shade.

In the form of my invention shown in Figs. 7 and 8, the openings 10 are in the form 35 of narrow slots 17.

If desired, a wick 18 of absorbent material may be inserted in the bead 9 for absorbing the perspiration which passes from the flange 7 through said slots into the bead 40 and such wick may be removed and replaced as desired.

From the foregoing it will be apparent that my device may be easily and quickly attached to a person's hat to prevent perspiration 45 from soiling the same or to afford an eye shade; and when such device is not required it may be easily and quickly detached without harm to the hat.

I claim:

50 1. A hat band protecting shield comprising a sheet of non-absorbent material; means for securing said sheet to the sweat band of a hat; a flange extending forwardly from the lower edge of said sheet for a short distance under the hat brim; and a bead on said flange provided with openings through which perspiration may pass from said flange into the bead.

60 2. A hat band protecting shield comprising a sheet of non-absorbent material; means for securing said sheet to the sweat band of a hat; a flange extending forwardly from the lower edge of said sheet under the hat brim; a bead on said flange provided with 65 openings through which perspiration may

pass from said flange into the bead; and a wick in said bead for absorbing the perspiration which enters the bead.

3. A hat band protecting shield comprising a sheet of non-absorbent material; means 70 for securing said sheet to the sweat band of a hat; a flange extending forwardly from the lower edge of said sheet under the hat brim; and a bead intermediate the ends of said flange and provided with openings 75 through which perspiration may enter said bead.

4. A hat band protecting shield comprising a sheet of non-absorbent material; means 80 for securing said sheet to the sweat band of a hat; a bead on said sheet provided with openings through which perspiration may pass from said sheet into said bead; and a wick in said bead for absorbing the perspiration which enters the bead.

In testimony whereof, I have hereunto set my hand at Los Angeles, California, this 21st day of November, 1927.

JOHN C. MORGAN.
